H. H. TERRY.
COMBINED WORK BAG AND RETICULE.
APPLICATION FILED MAR. 5, 1913.

1,081,788.

Patented Dec. 16, 1913.

UNITED STATES PATENT OFFICE.

HELEN H. TERRY, OF SOUTHAMPTON, NEW YORK.

COMBINED WORK-BAG AND RETICULE.

1,081,788.

Specification of Letters Patent. Patented Dec. 16, 1913.

Application filed March 5, 1913. Serial No. 752,077.

To all whom it may concern:

Be it known that I, HELEN H. TERRY, a citizen of the United States, and a resident of Southampton, in the county of Suffolk and State of New York, have invented certain new and useful Improvements in Combined Work-Bags and Reticules, of which the following is a full, clear, and exact description.

10 This invention relates to combined work-bags and reticules for use by nurses, maids or other persons while traveling and on other occasions, and has reference more particularly to a device of this class which comprises an outer bag or envelop having means whereby it can be closed, and an inner, foldable member having means for carrying different toilet or other articles, and adapted to be disposed within the outer envelop, 20 or to be withdrawn therefrom to render the articles thereon, available for use.

The object of the invention is to provide a simple, inexpensive and durable combined work-bag and reticule adapted for use at home or while traveling, which affords means for carrying toilet articles and the like and can be used by nurses, housemaids, or by other persons, which is simple and compact in form and light in weight, in 30 which the toilet or other articles are securely held in position against accidental displacement, which affords ample room for carrying needlework, small articles of clothing or other objects, and which can be attached to the person to render available the contents thereof, while leaving free the hands of the user.

The invention consists in the construction and combination of parts to be more 40 fully described hereinafter and particularly set forth in the claims.

Reference is to be had to the accompanying drawings forming a part of this specification, in which similar characters of reference indicate corresponding parts in all the views, and in which—

Figure 1 is a front view of an embodiment of my invention, showing the same closed; Fig. 2 is a rear view of the device, showing 50 the inner member withdrawn from the outer envelop; Fig. 3 is a similar, front view of the device; Fig. 4 is a front elevation showing the inner member open to render available the articles carried thereby; Fig. 5 is 55 a vertical section on the line 5—5 of Fig. 1;

and Fig. 6 is a similar view on the line 6—6 of Fig. 4.

Before proceeding to a more detailed explanation of my invention, it should be clearly understood that my combined work-bag and reticule can be fashioned from any suitable material adapted for the purpose, for example, from cloth, leather, waterproof material or the like. Likewise, any fastening devices adapted for the purpose 60 may be used, notwithstanding that I have shown for example, the usual button and socket snap fasteners for securing the edges of the inner member of the device. Needless to say this inner member may be provided with means for carrying toilet or other articles of any desired kind. These and others of the details of construction form no part of the invention and can be varied in accordance with individual preference and special conditions, without departing from the underlying spirit of the invention.

Referring more particularly to the drawings, I provide an outer bag or envelop 10 fashioned from a length of material folded upon itself to form the bottom edge 11 of the device, and sewed or otherwise secured along the lateral edges 12, leaving an opening 13 at the top. The upper edge portions of this member 14 are inturned at the opening 13 and sewn to form drawstring pockets or sleeves 15, in which is located the usual drawstring 16, which permits the mouth or opening at the top of the bag to be drawn 70 shut and fastened as is shown in Fig. 1.

Located within the outer envelop is the foldable inner member 17 secured near its transverse median line 18, by sewing or in any other suitable manner, to the inturned edge portion 14 at the back of the outer bag. The inner member consists preferably of two thicknesses 19 and 20, of fabric or other material of which the latter may be of waterproof character. It will be seen that the inner member 17 is so positioned within the outer envelop that it can be entirely withdrawn therefrom, as is shown in Fig. 6, being attached to the envelop only at the upper edge thereof. The inner member is provided along its side and upper edge portions with corresponding elements 21 and 22 of snap or other fasteners, so that it can be secured along these edges when folded within the outer bag. It is provided upon its 80 90 100 110

inner surface with straps 23 forming fasteners 24, or with other suitable means for holding in place different toilet or like articles 25.

- 5 At its upper edge the inner member 17 is provided with a sleeve or pocket 26 extending entirely across the end thereof and receiving therein a cord or ribbon 27. This serves to attach the device to the person of
10 the user, if necessary or desirable, the cord 27 being fastened about the waist, so that the device in its open position as shown in Fig. 4, can depend at the front of the person in the manner of an apron. This renders
15 available all the articles carried by the inner member 17, leaving the hands of the user free for other purposes. The outer bag or envelop itself forms a convenient reticule for carrying needlework or other articles.
20 If so desired, the inner member 17 may be provided with a rod or bar (not shown), so that it can be hung from a wall or other support to render the contents of the reticule available for use.
25 Having thus described my invention I claim as new, and desire to secure by Letters Patent:—

1. A device of the class described comprising an outer bag having an opening and means for closing said opening, an inner, foldable member secured within said bag, adjacent to said opening, and adapted to be wholly withdrawn from said bag, said inner

member being provided with means for carrying toilet or other articles, said inner 35 member further having means whereby it can be secured to the person, to permit the device to be supported upon the body of a person, in the manner of an apron.

2. A device of the class described, comprising an outer bag having an opening, an inner member foldable upon itself and secured substantially along its fold line, within said bag, adjacent to said opening, and having means for carrying toilet or 45 other articles.

3. A device of the class described, comprising an outer bag having an opening, an inner member foldable upon itself and secured substantially along its fold line, within said bag, adjacent to said opening, and having means for carrying toilet or other articles, said inner member being provided with fasteners to secure its edges together, and having means whereby, when withdrawn from said bag, it can be secured to the person of the user, to adapt the device to be carried in the manner of an apron. 50

In witness whereof I have signed my name to this specification in the presence 60 of two subscribing witnesses.

HELEN H. TERRY.
